UNITED STATES PATENT OFFICE.

JOHN E. MULRONEY, OF CHICAGO, ILLINOIS; MARGARET B. MULRONEY, EXECUTRIX OF SAID JOHN E. MULRONEY, DECEASED, ASSIGNOR TO EDWARD M. BRACKETT AND FRED BRACKETT, COPARTNERS, DOING BUSINESS AS THE BRACKETT STRIPPING MACHINE COMPANY, OF TOPEKA, KANSAS.

PAPER-CUTTING MACHINE AND GAUGE THEREFOR.

Application filed September 19, 1925. Serial No. 57,427.

This invention relates to paper cutting machines and gauges therefor, wherein a knife for cutting or trimming material, such for example as sheets of paper bound or unbound, is mounted in movable relation to a feed table or bed, and a gauge or means for positioning the material or for enabling the paper to be accurately placed and removably held in position to be operated upon. 5

10 is provided and adapted to be employed in conjunction with such a knife and feed table or with a paper cutting machine.

The principal object of this invention is to provide a simple, economical and efficient 15 paper cutting machine, and more particularly to provide an improved adjustable gauge mechanism or paper-positioning and holding means adapted to enable paper to be accurately positioned and removably held 20 in position to be operated upon by the knife or cutting mechanism of a paper cutting machine, with facility and with safety to the operator.

Other and further objects of the invention 25 will appear from the following description and claims, and from an inspection of the accompanying drawings which are made a part hereof.

The invention consists in the features, 30 combinations, details of construction, and arrangement of parts herein described and claimed.

In the accompanying drawings—

Figure 1 is a view in central vertical section, of a paper cutting machine provided 35 with gauge mechanism or paper-positioning and holding means constructed in accordance with my invention, and shows my improved adjustable gauge and gauge-stopping and releasing or positioning mechanism in elevation;

Fig. 2 is an enlarged detail view in side elevation showing my improved adjustable gauge mechanism or paper guiding and 45 positioning means operatively connected with the movable knife or knife-supporting and operating mechanism of a paper cutting machine such as is shown in Fig. 1;

Fig. 3 is an enlarged detail view taken on 50 line 3—3 of Fig. 2, looking in the direction indicated by the arrows, and shows the pawl

and ratchet mechanism and stopping and releasing means for setting or positioning the adjustable stops for stopping the adjustable or movable gauge in different predetermined adjusted positions successively; 55

Fig. 4 is a similar view taken on line 4—4 of Fig. 2 and showing the mechanism illustrated in Fig. 3 as it would appear upon being operated automatically by a movement 60 or operation of the knife and knife-supporting and operating mechanism, whereby the ratchet and the shaft on which it is mounted are rotated from the position shown in Fig. 3 to the position shown in said Fig. 4; 65

Fig. 5 is a horizontal or plan view partly in section, taken on line 5—5 of Fig. 2, looking downward as indicated by the arrows, and showing a top view of the gauge and gauge-stopping and releasing mechanism shown in Figs. 2, 3, and 4; 70

Fig. 6 is an enlarged detail plan view showing the movable or adjustable gauge in operative engagement with an intermediate stop; 75

Fig. 7 is an enlarged detail view taken on line 7—7 of Fig. 5, looking in the direction indicated by the arrows, and shows the stop-supporting rock shaft in section, provided with a plurality of adjustable stops thereon 80 on and movable therewith into and out of position to be engaged by the stop on the movable or adjustable gauge which extends over the feed table; and

Fig. 8 is an enlarged detail view showing 85 one of the adjustable stops on the stop-supporting rock shaft, and the means for adjustably connecting the stops with said shaft.

In constructing an improved gauge mechanism or paper-positioning and holding mechanism for paper-cutting machines, and a paper-cutting machine provided therewith, in accordance with my invention, I provide a paper cutting machine 1 having a main 95 frame 2, a feed table or paper-supporting bed 3, a reciprocating upwardly and downwardly movable knife or cutter 4, which is located above the level of and extends transversely across and in movable relation to the 100 feed table 3 and machine frame, said knife being slidably supported between upright

frame portions or vertical guiding ways 5, 5 formed by opposite upright side frame portions 6 located on opposite sides of the feed table and machine frame and forming a part 5 of said frame. The knife or cutter 4 is mounted in and movable upward and downward with a pair of slidable knife-supporting and guiding members 7 which are located on opposite sides of the frame and 10 feed table and between and in vertically slidable engagement with said upright guides or ways 5, 5.

The knife is not only movable upward and downward with the knife-supporting 15 members 7, but is also movable transversely with respect to said supporting-members 7, so that the path of movement of the knife is oblique with respect to the feed table and also with respect to the vertical path of 20 movement of the knife-supporting members or slides 7.

The knife or cutter 4 is operatively connected with suitable knife-operating mechanism, which may be of any ordinary and 25 well known or suitable form, and may comprise a pair of pitmen or connecting rods 8, located on opposite sides of the main frame and feed table and each having its upper end connected with a corresponding knife- 30 supporting member or slide 7 by means of a pivot pin 9, the lower end of each pitman 8 being connected with suitable driving mechanism, such, for example, as an electric motor or source of power 10, by means of 35 a crank shaft 11 having crank arms 12 operatively connected with the lower ends of the pitmen 8 by means of wrist pins 13, or other suitable connecting means, the crank shaft 11 being operatively connected with 40 the motor or source of power 10, by means of a train of gears and suitable shaft and clutch mechanism which may be of any desired ordinary and well known or suitable form.

45 In the machine shown in the drawings a spur gear wheel 14 is fixed to the rotative crank shaft 11 and is in toothed engagement with a spur pinion 15 fixed to a counter shaft 16, said counter shaft having a spur 50 gear wheel 17 thereon which is in toothed engagement with a pinion 18 on the motor shaft 19. Suitable clutch mechanism 20, which may be of any ordinary and well known or suitable form, is provided, for operatively connecting the knife and knife 55 operating or driving mechanism with the motor or source of power, and for disconnecting the same.

An upwardly and downwardly movable 60 clamp bar or paper-clamping member 21 having suitable clamp-operating mechanism which may comprise toothed racks 22 and rotative rack-operating pinions 23 supported on the machine frame and operatively connected with the vertically movable clamp 65

or clamping member 21, is provided and mounted in front of the knife and in position to extend transversely across the feed table, so as to releasably engage and hold the paper to be cut or operated upon, in 70 position to extend beneath and to be engaged and cut by the knife while the paper is clamped or held between the clamp and the feed table.

The mechanism above described may be 75 of any desired ordinary and well known or suitable form: The paper-cutting machine shown in the accompanying drawings is constructed as shown in my application for Letters Patent of the United States Serial No. 80 734,726 filed August 28, 1924, for improvements in paper-cutting machines.

My improved gauge mechanism or paper-positioning and adjustable stops and stop-operating mechanism, however, is intended 85 and adapted to be attached to or used in connection with various forms of paper-cutting machines. Such machines being in common use and well known in the art to which 90 this invention relates, it is deemed unnecessary to further describe the same in detail herein.

My improved gauge mechanism or paper-positioning mechanism, which includes a 95 movable gauge and one or more adjustable stops for stopping or positioning such movable gauge, and means for adjusting or setting such stop or stops, is constructed and adapted to operate as follows:

A stationary upright gauge or gauge- 100 guide 24 is mounted upon or adjacent to one side of the feed table 3 and in position to extend at right angles to the knife 4. A movable or adjustable upright transverse gauge 25 is slidably mounted in engagement 105 with and adapted to be guided by said stationary gauge or gauge-guide 24 and in position to extend at right angles to the latter and transversely over or part-way across the upper surface of the feed table and in parallel relation to the knife. The bottom of the movable gauge 25 is, by preference, in slidable engagement with the top surface of the feed table, and is movable lengthwise of the stationary gauge or gauge-guide 24 to 110 different adjusted positions successively, as required.

The movable transverse gauge 25 is, by preference, provided with a forwardly extending portion or head 26 having a top plate or flange portion 27 which extends over and transversely beyond the top edge of the stationary gauge or gauge-guide 24. And a depending flange 28 on the top plate 27 slidably engages the outer side of the stationary gauge member 24. The transverse flanged arm portion 29 of the movable transverse gauge 25 is adjustably secured in fixed relation to the forwardly extending portion 26 by means of a thumb screw 30 which ex- 115 120 125 130

tends through an elongated horizontal slot in the upright flange portion 31 of said gauge member 25.

- A laterally projecting stop finger 32 is 5 mounted on and pivotally connected with the upper forward portion 26 of the movable transverse gauge 25 by means of a horizontal pivot pin 33. (See Figs. 6 and 7.) The inner end portion 34 of the stop finger 10 32 is cut away on its inner side so as to permit the outer end of said stop finger to swing upward. The inner end portion 34 thus forms a handle by means of which said stop may be operated when required. And the 15 outer or stop-engaging end of the stop finger 32 is cut away so as to form a triangular or wedge-like portion 35 having an inclined surface which is adapted to permit the stop finger 32 to pass one or more stops 36, 37, 20 38, respectively, as the stop finger 32 is moved with the movable gauge 25 in one direction, but cause said stop finger 32 to engage and be stopped by any one or more of said stops 36, 37, 38 whenever such stationary stop or stops are set or adjusted 25 into position to operatively engage or extend into the path of movement of said stop finger and the latter is moved in an opposite direction.
- 30 The stationary adjustable stops 36, 37, 38,—of which there may be any desired number, and of which a series or set of three are shown in the drawings—are adjustably mounted upon a stop-supporting and operating member or rock shaft 39 which is rockingly or rotatively mounted in suitable bearings in a frame arm or bracket 40 at the forward extremity of the shaft or stop-supporting member 39 and feed table, and in 35 the upright frame portion 6 at the rear extremity of said shaft or stop-supporting member 39. The stop-supporting member or rock shaft 39 is located outside of the stationary gauge or gauge guide 24 and in 40 parallel relation to the same.

Each of the gauge stops 36, 37, 38 is, by preference, adapted to be adjusted or moved to and releasably secured in different adjusted positions both lengthwise and circumferentially of said shaft or stop-supporting member 39. And said shaft or stop-supporting member 39 is adapted to be rocked or rotated intermittently or in a step-by-step manner in one direction for setting or moving the stops 36, 37, 38 into position to successively engage and stop the stop finger 32 on the movable transverse gauge 25, in a desired or predetermined order, and in an opposite direction to cause said stops 36, 37, 45 38 to be returned to initial position or out of the path of movement of the stop finger 32 on said movable transverse gauge 25.

In order to enable the stops 36, 37, 38 to be adjusted with facility either longitudinally or circumferentially of the shaft

or rotative stop-supporting member 39, as desired, each of said stops is, by preference, provided with an annular main body portion in the form of a sleeve or split ring 41 having 70 projecting ends 42 provided with perforations in which is mounted a clamping screw 43, for releasably securing said annular split sleeves or body portions of the stops in position upon said shaft 39 which extends through the annular split sleeves or body 75 portions of the said stops thus formed. Each of said stops is also, by preference, provided with a spring-pressed securing member in the form of a steel ball or spring-pressed bolt 44, or equivalent element, 80 mounted in a recess in said stop containing a compression spring 45 held in place by a cap or screw 46 in the projecting end or stopping finger portion of such stop. The 85 rotative or rock shaft 39 is provided with a series of parallel longitudinal peripheral grooves 47, of which there may be any desired number, each adapted to receive any desired or predetermined spring-pressed ball 44 of any corresponding stop 36, 37 or 38, as 90 the case may be, whenever such stop is adjusted circumferentially of the shaft into position to cause such spring-pressed member or ball to enter such slot. The front 95 stop 36, intermediate stop 37 and rear stop 38 are thus adapted to be adjusted independently of each other circumferentially of the rotative stop-supporting shaft 39, to as many different adjusted positions on said shaft as there are peripheral grooves 47 in 100 the shaft.

For example, the forward stop 36 may be moved or adjusted circumferentially of the shaft into such position that its spring-pressed ball 44 will enter the proper peripheral groove 47 to cause the projecting end of such stop to be the first one of the series of stops to move into and stop in the path of movement of the stop-finger 32 on the movable transverse gauge 25, thus causing said 110 movable gauge 25 to be stopped in the proper position for positioning the paper with respect to the knife and paper-clamping member. The forward stop 36 thus adjusted, is 115 in position to serve as the stop for stopping the movable transverse gauge 25 and the paper engaged by such gauge, in position for the first cut. The paper-engaging clamp and knife are then operated for making the 120 first cut.

The intermediate stop 37, having been adjusted circumferentially of the shaft or rotative stop-supporting member 39 into such position that its spring-pressed ball or member 44 will enter another peripheral longitudinal groove 47, for example, the groove which will cause said intermediate stop 37 to be the third one of the series of stops to move into and stop in the path of movement 125 of the stop-finger 32 on the movable trans-

verse gauge 25; and the rear stop 38 having been adjusted circumferentially of the rock shaft or rotative stop-supporting member 39 into such position that its spring-pressed ball or member 44 will enter still another longitudinal peripheral groove 47; for example, the groove which will cause said rear stop 38 to be the second one of the series of adjustable gauge-stops to move into and 10 stop in the path of movement of the stop-finger 32 on the movable transverse gauge 25, it will be readily understood that the rear stop 38 when thus adjusted is in position to serve as the stop for stopping the movable 15 transverse gauge 25 and the paper engaged by such gauge, in the proper position with respect to the knife and paper-engaging clamp for the second cut. It will also be readily seen that the intermediate stop 37, 20 being in position to be the third one of said stops to move into and stop in the path of movement of the stop-finger 32 on the movable gauge 25, as the rotative or rock shaft 39 on which said series of stops is mounted, 25 is in position to serve as the stop for stopping the movable transverse gauge 25 and the paper engaged by such gauge, in the proper position with respect to the knife and paper-engaging clamp, for enabling the 30 third cut to be made in its order. (See Figs. 2, 5, 6, 7, and 8.)

From the foregoing it will be readily understood by those skilled in the art to which this invention relates that the stops 36, 37, and 38 are adapted to be adjusted independently of each other circumferentially of the rock shaft or stop-supporting member 39, into such position with respect to each other and with respect to the direction 40 of rotation of the shaft on which said stops are fixed so as to rotate or rock with the shaft, that the projecting fingers or ends of said stops may be caused to move into and to stop in the path of movement of the stop-finger 32 on the movable gauge 25 in any desired predetermined order. For example, the intermediate stop 37 may be adjusted to position to be the first to engage the stop 32, for the first cut; the first or forward stop 36 45 being adjusted to position to be the second to engage the stop 32, so that the gauge 25 will be positioned properly for the second cut; and the rear stop 38 may be adjusted to position to be the third one of said series of 50 stops on the rotative stop-supporting shaft 39 to engage the stop-finger 32 on the movable transverse gauge 25, so that the gauge 25 will thereby be positioned properly for the third cut.

Ordinarily in cutting sheets which are bound together in the form of a book or pad, only three cuts are necessary. And from the foregoing description, it will be readily understood that the cuts may be 55 made along the long or short margins of

the sheets in any desired order, the adjustable gauge stops 36, 37 and 38, or any desired number of such stops being set in the proper positions relatively to each other and to the direction of rotation of the supporting shaft upon which they are mounted and with which they are adapted to revolve or move as the shaft is rotated, so that each of said stops will serve in its order according to its position on the rotative stop-supporting shaft, to engage the stop-finger 32 on the movable transverse gauge 25 and position said gauge and the paper engaged by the gauge ready for cutting. 70

Means is provided for rotating or partially rotating the stop-supporting shaft 39 intermittently or in a step-by-step manner in one direction and thereby automatically moving the gauge-stops on and rotative with said shaft into position to operatively engage and stop the stop-finger 32 and movable transverse gauge 25 in different predetermined positions successively in the desired predetermined order, said stops having been first adjusted to and secured in the proper positions respectively lengthwise and circumferentially of said stop-supporting shaft so that such rotation or partial rotation of the shaft will cause said stops to be moved into and stopped in the path of movement of the stop 32 in the desired predetermined order, according to the cuts to be made. And means for automatically returning the stop-supporting shaft and the stops thereon to initial position is also provided, although it will be understood from the foregoing that the shaft can be rotated or rocked or partially rotated in either direction manually, thereby causing the gauge-stops on said shaft to be moved into and away from gauge-stopping 95 position. 100

The stop-supporting and operating shaft 39 is, by preference, provided with a toothed ratchet wheel 48 fixed thereto, said ratchet wheel being located at the rear extremity of the shaft and adjacent to the vertically movable slide 7 which supports and guides the knife 4 and is connected with and operated by the pitman mechanism or knife-operating mechanism above described. 110

A reciprocating pawl 49 having a toothed or hooked end portion adapted to engage the teeth of the ratchet wheel 48 is pivotally mounted on a depending arm 50 of a bell-crank lever 51 which, by preference, comprises a horizontal rock-shaft 52 having crank-arms or lever arms 50 and 54 fixed to opposite ends of said shaft, said bell-crank lever being rockingly supported in a stationary frame portion or bracket 53 on an upright side frame member 6, or other stationary support. 120

The bell crank lever 51 has a lever arm 54 which is disposed at an angle to the depending lever arm 50 and adapted to be opera- 125 130

tively connected with or engaged by a projecting element or boss 55, or equivalent crank-operating or engaging means on the vertically movable slide 7 or connected with 5 and adapted to move upward and downward with the knife 4. The slide 7 with its boss 55, the bell crank 51, the pawl 49 and ratchet wheel 48 thus serve to operatively connect the gauge-stops on the shaft 39 with the 10 knife and knife operating mechanism, so that the operation of the knife will cause the shaft 39 to rotate intermittently and actuate or move the gauge stops mounted on said shaft into position to operatively engage 15 said stop-finger 32 on the movable gauge 25 in the required predetermined order for positioning the gauge 25 and the paper to be cut. The pawl 49 is operated in one direction by the bell crank 51 when the knife 4 and 20 knife supporting slide 7 with the boss 55 are at or near the position reached by the downward stroke of the knife. Each movement of the pawl in the direction required for operating the pawl will cause the ratchet 25 wheel and the shaft 39 to rotate one step, each step corresponding with one ratchet tooth and with a required adjusted position of the movable gauge 25 and a corresponding cut. A spring 56 on the pin 57 which supports the pawl and the bell crank 51, serves 30 to return the bell crank and pawl to initial position after each operation of said pawl and the shaft 39 by the downward movement of the knife.

35 A stopping and releasing pawl or detent 58 is pivotally supported by a pin 59 in position to engage and release the toothed ratchet wheel 48, said detent having a tooth or arm 60, which is adapted to engage the 40 teeth of said ratchet wheel, and a lower tooth or arm 61 in fixed relation to the arm 60 and in position to be actuated by a pin 62 forming a boss on the ratchet.

The pin or boss 62 is adjustable to different positions with respect to the ratchet wheel 48, and is, by preference, removably mounted in any desired one of a series of perforations 63, 64, 65, 66, 67, of which there may be any desired number in said ratchet 50 wheel or similar perforated member fixed to the shaft 39. Each of said perforations corresponds with a tooth on the ratchet wheel, there being such a tooth and a corresponding perforation for each adjusted position into 55 which the movable transverse gauge 25 is adapted and intended to be moved or adjusted. And said movable gauge is of course adapted to be moved to a predetermined position for each cut respectively.

60 The pin or boss 62 is thus adapted to engage and raise or release the pawl or detent 58 from engagement with the toothed ratchet wheel 48 whenever said ratchet wheel and the shaft 39 on which it is fixed is rotated 65 a sufficient number of steps to cause the pin or boss 62 to engage and raise the arm 61 of said detent 58 so as to cause the arm or finger 60 to be raised out of engagement with the toothed ratchet wheel. (See Figs. 3 and 4.)

70 Whenever the detent arm or finger 60 is thus raised out of engagement with the ratchet wheel, the latter and the shaft 39 will be thereby released and free to return to initial position. A helical spring 68 is operatively connected with and adapted to rotate the shaft 39 and the ratchet wheel and stops fixed to said shaft, to initial position whenever the stopping and releasing pawl or detent 58 is released by the pin 62. The 75 pawl or detent 58 may be termed a latch; and a latch-returning pin 69 on the ratchet wheel 48 is adapted to engage the arm 61 of the latch and return said latch to its initial position whenever the ratchet 48 and shaft 39 return to their initial position.

80 A spring-pressed bolt or yielding stop 70 is mounted in a recessed or socket member 71 in position to engage one side of a shoulder 72 on the latch or detent 58, for holding said latch in engagement with the ratchet wheel 48, and is adapted to engage the opposite side of said shoulder 72, or a notch 73 in said latch member, for holding the same out of engagement with the toothed ratchet 85 wheel 48 when the latter is released for the purpose of permitting it to return to initial position.

85 From the foregoing it will be readily seen that by mounting the pin 62 in perforation 100 63, the latch 58 will be released for permitting the shaft 39 and the gauge-stops thereon to return to initial position upon the completion of a predetermined cut, for example a first cut; that by mounting said pin 62 in another perforation, for example perforation 64, the latch 58 will be engaged by said pin and released and the shaft 39 and its stops 36, 37, 38 will be permitted to return to initial position upon the completion of another predetermined cut or cutting operation, for example the second cut; and that by mounting the pin 62 in still another perforation, for example perforation 65 the 105 latch 58 will be engaged and the shaft 39 and the stops thereon released and permitted to return to initial position upon the completion of a corresponding cut, for example a third cut, and so on for as many cutting operations as may be required.

110 I claim:

1. In a cutting machine having a movable knife, the combination of a feed table, a movable transverse gauge adapted to extend over a portion of the feed table, a gauge-guide in engagement with said movable transverse gauge, a series of movable gauge-stops, and means for moving said gauge-stops into and out of position to operatively engage said movable gauge, for stopping the 115 120 125 130

same in different predetermined positions successively.

2. In a cutting machine having a movable knife, the combination of a feed table, a movable transverse gauge adapted to extend over a portion of the feed table, a gauge-guide in engagement with said movable transverse gauge, a series of gauge-stops mounted in adjustable relation to each other and to the feed table, and means for moving said gauge-stops into position to operatively engage said movable gauge, for stopping the same in different adjusted positions successively.

3. In a cutting machine having a movable knife, the combination of a feed table, a movable gauge adapted to extend over a portion of the feed table, a gauge-guide in engagement with said movable gauge, a series of movable gauge-stops mounted in adjustable relation to each other and to the feed table, means for operating the knife, and means operatively connected with the knife-operating means, for automatically operating said gauge-stops, for stopping the movable gauge in different adjusted positions successively.

4. In a cutting machine, the combination of a knife, a feed table extending forward of the knife, a movable gauge adapted to extend transversely over a portion of the feed table, a gauge-guide in engagement with said movable gauge, a movable gauge-stop for stopping said movable gauge in a predetermined position with respect to the knife, and operating means operatively connected with the knife and with said gauge-stop and adapted to automatically move the gauge-stop into position to operatively engage and stop said movable gauge.

5. In a cutting machine, the combination of a knife, a feed table extending forward of the knife, a movable gauge located forward of the knife and adapted to extend over a portion of the feed table, means for guiding said movable gauge, a movable gauge-stop for stopping said movable gauge in a predetermined position with respect to the knife, and operating means operatively connected with the knife and with said gauge-stop respectively and adapted to operate said knife and gauge-stop synchronously with respect to each other.

6. In a cutting machine, the combination of a knife, a feed table extending forward of the knife, a movable gauge adapted to extend over a portion of the feed table, means for guiding said movable gauge, a plurality of movable gauge-stops mounted adjacent to said movable gauge, and operating means operatively connected with the knife and with said gauge-stops and adapted to operate said knife and gauge-stops synchronously with respect to each other.

7. In a cutting machine, the combination of a knife, a feed table extending forward of the knife, a movable gauge located for-

ward of the knife and adapted to extend over a portion of said feed table, a gauge-guide, for guiding said movable gauge, a series of gauge-stops mounted in adjustable relation to each other, and operating means operatively connected with the knife and with said series of gauge-stops and adapted to operate said knife and said series of gauge-stops synchronously with respect to each other.

8. In a cutting machine, the combination of a knife, a feed table extending forward of the knife, a movable gauge adapted to extend over a portion of the feed table, a gauge guide, for guiding the movable gauge, a series of gauge stops, a rotative supporting member upon which said stops are mounted in adjustable relation to each other, means for rotating said gauge-stop supporting member intermittently, for moving the gauge-stops into position to operatively engage and stop said movable gauge in different predetermined positions successively, and means for operating the knife.

9. In a cutting machine, the combination of a knife, a feed table extending forward of the knife, a movable gauge adapted to extend over a portion of said feed table in movable relation to the knife, a series of gauge-stops, a rotative supporting shaft upon which said stops are adjustably mounted, and operating means operatively connected with said knife and said stop-supporting shaft and adapted to operate said knife and shaft synchronously with relation to each other.

10. In a cutting machine, the combination of a knife, a feed table extending forward of the knife, a movable gauge adapted to extend over a portion of said feed table and in front of the knife, a plurality of gauge-stops for stopping said movable gauge, a rotative supporting shaft upon which said gauge-stops are mounted, means for operating the knife, and shaft-operating means operatively connected with the knife and knife-operating means and with said rotative stop-supporting shaft, for operating said shaft and gauge-stops.

11. In a cutting machine, the combination of a knife, a feed table extending forward of the knife, a movable gauge adapted to extend over a portion of said feed table, a plurality of gauge-stops, for stopping said movable gauge, a rotative stop-supporting shaft upon which said stops are adjustably mounted, means for operating the knife, and pawl and ratchet mechanism operatively connected with said stop-supporting shaft and with the knife-operating means, for operating the stop-supporting shaft.

12. In a cutting machine, the combination of a knife, a feed table extending forward of the knife, a movable gauge adapted to extend over a portion of said feed table and in

movable relation to the knife, a series of gauge-stops, for stopping said movable gauge, a rotatable stop-supporting shaft upon which said gauge-stops are adjustably mounted, pawl and ratchet mechanism operatively connected with said stop-supporting shaft and adapted to rotate said shaft intermittently in one direction, for moving said gauge-stops into position to operatively engage and stop said movable gauge in different predetermined positions successively, and means for releasing and returning said stop-supporting shaft to initial position. 20

5 means for supporting and operating the knife, a ratchet wheel fixed to said rotative stop-supporting shaft, a reciprocating pawl mounted in engagement with said ratchet wheel, and pawl-operating means operatively connected with said pawl and with said knife-operating means. 25

13. In a cutting machine, the combination of a knife, a feed table extending forward of the knife, a movable gauge adapted to 15 extend over a portion of said feed table and in front of the knife, a series of gauge-stops, Signed at Chicago, in the county of Cook and State of Illinois, this 29th day of August, 1925. 30

JOHN E. MULRONEY.
